R. B. TRACY

LIQUID DISPENSING DEVICE

Filed July 2, 1928

Inventor:

R. B. Tracy,

By W. C. Williams Atty.

Patented Feb. 26, 1929.

UNITED STATES PATENT OFFICE.

ROBERT BENEDICT TRACY, OF CHICAGO, ILLINOIS.

LIQUID-DISPENSING DEVICE.

Application filed July 2, 1928. Serial No. 289,637.

My invention relates to that class of household, hotel and office appliances for serving water and beverages of various kinds, the device to be used in hotel rooms, on the house-
hold table, or in offices where ordinarily a pitcher or bottle of water is commonly used for supplying drinking water or beverages.

The object of my invention is to provide a very simple device by means of which a person may get a drink, if desired, with the least effort and not require the lifting up of any bottle or pitcher in order to pour out the contents of a single serving.

Reference will be had to the accompanying drawings in which Fig. 1 is a front elevation of my device.

Fig. 2 is a vertical sectional elevation transversely of Fig. 1.

Fig. 3 is a plan view on line 3—3 of Fig. 2. The liquid to be served is carried in a bottle indicated by 2 here shown as an ordinary bottle but in general service this will be what is known as a vacuum bottle being a double walled bottle having a vacuum space in between as is commonly used for keeping its contents either hot or cold without serious loss by radiation.

The bottle 2 is contained within a case having a base plate 3 provided with an annular screw flange 4 screwed into a screw threaded ring 5 into a square base member 6 which is merged into a portion of smaller diameter 7 which is covered at the top by cap 8 the cap 8 being provided with flanges 9 that are secured to the top of the rectangular walls of the portion 7. On the inner side of the cap plate 8 there is secured a plug 10 and projecting through this plug 10 extending down toward the bottom of the bottle there is the tube 11. A vent hole 12 passes through the plug 10 into the top of the neck of the bottle where a slight ventilation or release of vacuum takes place as the liquid is taken out of the bottle. Secured tightly to the cap 8 there is a square tubular upward extending portion 13 simulating what might be termed an old-fashioned wooden square pump and this portion 13 acts as a pump cylinder into which there is mounted a suction block 14 connected at 15 to a pump rod 16 connected at 17 to a pump handle 18 hinged at 19 to a swinging block 20 hinged at 21 to the square cylinder portion 13. A ball 22 shown in dotted lines in Fig. 2 furnishes a valve for the suction block 14. A similar ball 23 furnishes the foot valve for the pump cylinder

portion 13. Thus there is arranged a small pump with its lower pipe and extending down into the interior of the bottle 2. A gasket 24 (see Fig. 2) closes the mouth of the bottle to steady the bottle in position and make a tighter closure to prevent any foreign matter or dirt to get in on the inside of the bottle.

An angular shoulder 25 in the base plate 3 steadies the bottom of the bottle in position as the same is inserted inside the casing. On the outside of the portion 7 there are some hooks or brackets 26 on which are hung small glasses or little buckets 27 through the medium of bails 28 which buckets may be hung onto a spout 29 of the pump cylinder portion 13, thus making it unnecessary to hold the cup or glass by hand under the spout 29 at the time the pump handle is worked in drawing fluid from the bottle into the glass 27. These cups or glasses 27 may be made of metal or any material suitable for the purpose.

The device as a whole makes a very convenient article with which to serve a drink of water or beverage without the necessity of lifting up a bottle or pitcher and it is a safety device as well since in handling a bottle or pitcher and lifting it up it frequently slips out of the person's hand by accident resulting in dropping the bottle or pitcher which accidents often result in the breaking of the bottle or pitcher and with my way of serving the liquid no such danger of accident is encountered as is the case with bottles or pitchers normally used in hotel rooms and on serving tables. Further, no gas pressure is required in withdrawing the material from the bottle or container in serving.

Claims:

1. In an apparatus for dispensing beverages and the like, a container adapted to hold a bottle in which is carried a fluid to be served, said container having an enclosure adapted to enclose the entire bottle and having an opening in the bottom thereof through which the said bottle is inserted and a plug on the inside of the said container adapted to register with and hold the neck of the bottle in place and a base bottom adapted to screw upward into the container and hold the bottle in place inside of the container, a pump extending above the container and a pipe running down into the interior of the container and into the interior of the bottle and adapted to pump the contents of the bottle

upward and discharge it into any suitable receiving cup.

2. In an apparatus for dispensing beverages and the like, an enclosing container for a bottle, said container having an opening in the bottom through which a bottle is adapted to be inserted upwardly, a registering plug in the upper end of the container adapted to engage the orifice of the bottle, a vent hole extending through the said plug, a pump arranged on the top of the container and having a pipe extending down through the said pump and into the interior of the bottle and a handle for operating the said pump.
3. In an apparatus for dispensing beverages and the like, a container for holding a bottle, a base plate forming the bottom of the container and adapted to be removed for the entrance of a bottle to the container, a cover fixed on the top of the container and a plug fixed in the cover and adapted to enter into and engage the nozzle of the bottle, an elastic gasket surrounding the said plug and adapted to make a close fit into the orifice of the bottle, a vent hole extending through the plug up into the interior of the container, a pump mounted on the top of the said container, a pipe extending down into the interior of the bottle, a pump spout simulating an ordinary water pump and adapted to hold a bucket by a bail and a pump handle adapted to work the said pump, the said pump being permanently fixed to the top of the said container.
4. In an apparatus for dispensing beverages and the like, a container enclosing a bottle and having an opening in its base and said opening closed by a screw threaded base cap and said cap having a seat adapted to register the base of the bottle in position and the said container having a flat cap permanently secured to the top of the said container, a plug on the inside of the said cap and a gasket mounted on the said plug, the said plug and gasket adapted to enter into the orifice of the neck of the bottle, a pipe extending down through the said plug and

into the interior of the bottle held within the container, a pump affixed to the top of the said cover of the said container and connected to the said pipe and adapted to pump the contents of a bottle contained within the container upward and discharge it through a laterally directed pump spout.

5. In an apparatus for dispensing beverages and the like, in combination, a container having an open bottom, a bottle containing the fluid to be dispensed insertable in said bottom and into the confines of the container, a plug immovably secured to the upper wall of the container for engaging the mouth of the bottle, a tube extending through the plug and downwardly into the bottle, a cylinder mounted upon the upper plate of the container and having a discharge outlet, a reciprocal pump operable within the cylinder for withdrawing the liquid from the bottle through said tube and discharging it through the outlet.

6. In an apparatus for dispensing beverages and the like comprising a container having an enlarged lower mouth portion and a relatively constructed upper portion, a bottle adapted to be received through the mouth of the receptacle and movable means for retaining the bottle within the confines of the receptacle, a stopper fixedly secured to the upper wall of the receptacle and centrally located with respect thereto for engaging the mouth of the bottle, a tube extending downwardly through said stopper and into the interior of the bottle, pumping mechanism superimposed and secured to the top of the receptacle and including a cylinder adapted to contain a determined quantity of water with valvular means preventing the return thereto to the bottle, and a piston operable in said cylinder to withdraw and discharge liquid from the cylinder through an outlet provided thereby.

Signed at Chicago, in the county of Cook and State of Illinois, this 20th day of June, 1928.

ROBERT BENEDICT TRACY.
